WIRE STRAIGHTENER

Charles D. Johnson, Worcester, Mass., assignor to
 Johnson Steel & Wire Company, Inc., Worcester,
 Mass., a corporation of Massachusetts

Application February 20, 1942, Serial No. 431,673

2 Claims. (Cl. 140—148)

This invention relates to wire straighteners of that type which comprises two rows of rolls between which the wire to be straightened passes, the rolls of one row being staggered with respect to the rolls of the other row and the two rows of rolls having a slightly overlapping relation so that as the wire is drawn between them, it is subjected to a multi-flexing operation by being bent first in one direction and then in the other as it contacts with the successive rolls.

In wire straighteners of this type, it is important that the rolls should always be capable of turning freely, for if any roll sticks and does not have a free turning movement the wire will have a sliding instead of a rolling contact therewith, a condition which produces a different straightening effect than if the roll was freely rotatable and thus had a rolling contact only with the wire.

The free rotation of the rolls can be secured by mounting them in ball bearings, and one of the objects of the present invention is to provide a wire straightener having relatively small rolls and in which the rolls are mounted in ball bearings in a novel way. In order to give an understanding of the invention, I have illustrated in the drawing a selected embodiment thereof which will now be described after which the novel features will be pointed out in the appended claims.

In the drawing,

Fig. 1 is a top plan view of a wire straightener embodying my invention with parts broken out to better show the construction.

Fig. 2 is an end view of Fig. 1.

Fig. 3 is a section on the line 3—3, Fig. 1.

Fig. 4 shows a roll such as is used in one of the rows of rolls.

Fig. 5 is a similar view showing the roll which is used in the other row of rolls.

The wire straightener herein shown comprises two roll-carrying blocks 3 and 4, each of which carries a row of straightening rolls, the rolls mounted in the block 3 being indicated at 5 and those mounted in the block 4 being indicated at 6. As the wire 8 to be straightened is drawn between the two rows of rolls it is subjected to a flexing action thereby, as is usual in wire straighteners of this type. The roll-carrying blocks 3 and 4 are adjustably mounted on a bed 7 so that said blocks may be adjusted toward and from each other to vary the degree of flexing which the wire receives when it passes between the two rows of rolls.

As herein shown, the block 3 is retained in position on the base 7 by means of clamping bolts 9 that pass through slots 10 in said block and said

block is adjusted on the bed by means of adjusting screws 11 which are screw threaded through arms 12 rising from the bed and which engage the rear face of the block 3. The clamping bolts 9 and their clamping nuts 13 provide for clamping the block 3 in any adjusted position. A similar construction is provided for adjusting the block 4 and for clamping it in an adjusted position. Said block 4 is provided with slots 14 through which extend clamping bolts 15 carrying clamping nuts 16. 17 indicates adjusting screws which are screw threaded through arms 18 rising from the base 7 and which engage the back side of the block 4. The block 3 is shown as having a positioning screw 19 at each end which is screw-threaded through an extension 20 on the block and engages the inner face of the block 4. These screws serve as means to limit the adjusting movement of the blocks toward each other. Each positioning screw 19 carries a lock nut 21 to assist in retaining it in its adjusted position.

For some purposes, it is desirable to use relatively small rolls in a wire straightener of this type and in order to provide for mounting such small rolls in ball bearing assemblies such as can be purchased on the market, I have adopted the construction which will now be described.

The block 3 is formed with two laterally extending flanges 22 and 23 that are directed toward the block 4 and form between them a channel or space 24 in which the rolls 5 are received. Each roll 5 is provided with two spindles 25, one on each side thereof, and these spindles are rotatively mounted in ball bearing assemblies 26 that are carried in the bearing flanges 22 and 23. Each ball bearing assembly is of the usual commercial type which comprises an inner ball race 27 in which the spindle 25 of the roll is received, an outer ball race 28 which fits into a circular opening or pocket 29 formed in the bearing flange, and a series of balls 30 between the ball races.

The rolls 6 carried by the block 4 are similarly mounted in bearing flanges 31 and 32 which extend laterally from the inner face of said block 4 and are directed toward the block 3 and which form between them a space 33 in which the row of rolls 6 is received. Each roll 6 is provided with two spindles 34 which are journaled in ball bearing assemblies 26 such as those above described and which are carried in the bearing flanges 31, 32. The flanges 22 and 23 on the block 3, and also the flanges 31 and 32 on the block 4 are wide enough to accommodate the smallest ball bearings assembly 26 which is now available on the market and inasmuch as the rolls 5 and 6 are relatively

small in diameter, smaller in fact than each ball bearing assembly 26, the straightening rolls of each set are situated entirely within the corresponding roll-receiving channel 24, 33 and the edge faces of the flanges are located outside of or beyond the periphery of the rolls.

In order to provide for the two sets of straightening rolls 5 and 6 being so placed relative to each other that the wire 8 will be given the required alternate bends in opposite directions while passing between said rolls, I have employed the construction shown in which the marginal portions of the flanges 22 and 23 on the block 3 have an overlapping relation with respect to the marginal portions of the flanges 31 and 32 on the block 4. This is provided for by spacing the flanges 31 and 32 on the block 4 far enough apart to receive between them the flanges 22 and 23 on the block 3 as clearly shown in Figs 2 and 3.

The rolls 6 are therefore made with spindles 34 which are of considerably greater length than the spindles 25 of the rolls 5, said spindles 34 of each roll 6 being long enough so that the ends of the spindles can be journaled in the ball bearings 26 carried by the widely spaced flanges 31 and 32.

Each of the flanges 22 and 23 is made with a scalloped inner face 35 as shown in Fig. 1, the indentations 36 in said face coming opposite the spindles 34 of the rolls 6. This construction, together with the overlapping relation of the flanges 22, 23 and 31, 32 permits the blocks 3 and 4 to be adjusted to give the maximum desired amount of bend to the wire 8, notwithstanding the fact that the rolls are relatively small in size and each is located entirely within its roll-receiving channel and is mounted in two ball bearings.

I claim:

1. A wire straightener comprising two roll-supporting blocks, each having two spaced bearing flanges forming between them a roll-receiving channel, said roll-supporting blocks being disposed in opposed relation with the bearing flanges

5 on each block directed towards the other block a plurality of straightening rolls in the channel of each block, each roll having two spindles, one on either side thereof, a pair of ball bearing assemblies for each roll in which the spindles of the roll are mounted, one ball bearing assembly of each pair being mounted in each flange of the corresponding block, the bearing flanges on one block being spaced apart sufficiently to receive 10 between them the bearing flanges on the other block and the marginal portions of the flanges on each block having an overlapping relation with respect to the marginal portions of the flanges on the other block, and means to adjust said 15 blocks toward and from each other.

2. A wire straightener comprising two roll-supporting blocks adjustable toward and from each other, each block having two spaced bearing flanges extending from that side thereof which 20 faces the other block, the bearing flanges of each block forming between them a roll-receiving channel, a series of relatively small straightening rolls in each channel, each roll having two spindles, one on each side thereof, a pair of ball 25 bearing assemblies for each roll in which the spindles of the roll are mounted, one ball bearing assembly of each pair being carried by each flange of the corresponding block, each straightening roll being smaller than the ball bearing assembly in which it is mounted and being located 30 entirely within its channel, the bearing flanges on one block being spaced apart sufficiently to receive between them the bearing flanges on the other block and the marginal portions of the flanges on each block having an overlapping relation with respect to the marginal portions of the flanges on the other block, thereby to permit the 35 two series of relatively small straightening rolls being so placed relative to each other that the wire passing between them will be bent first in one direction and then in the other.

CHARLES D. JOHNSON.
